UNITED STATES PATENT OFFICE

GEORGE T. HORTON, OF CHICAGO, ILLINOIS

CONTAINER

Application filed October 17, 1928. Serial No. 313,092.

This invention relates to improvements in containers, and is here shown as embodied in a container especially adapted for holding liquids under pressure.

5 The container here shown resembles to a certain extent, the container shown in my prior United States Patent No. 1,622,787 issued March 29, 1927 to which I refer.

In the prior patent referred to I showed a 10 container with a particular curvature and pointed out the advantages thereof. In that patent I showed a container with a flat bottom. I have found that in some cases it may be advantageous to use a curved bottom instead of a flat bottom. By making the bottom curved, I find that the container when 15 empty or nearly empty of liquid is better able to resist internal gas pressure. As an example, the curved bottom is here shown 20 curved as a segment of a sphere. When the container is nearly empty of liquid and has considerable gas pressure, there is a tendency for the edges of the bottom to be pulled or curled upwardly by an excess of internal gas 25 pressure. In such cases there is not sufficient weight or head of liquid to hold the bottom down. By making the bottom curved this tendency to distort the same is lessened 30 and the entire structure is strengthened.

Other features and advantages of my invention will appear more fully as I proceed with my specification.

In that form of device embodying the features of my invention shown in the accompanying drawings, Figure 1 is a diagrammatic view to assist in explaining the curvature of the container, and Fig. 2 is a view partly in side elevation and partly in vertical section.

40 The diagrammatic view shown in Fig. 1 is equivalent to a vertical sectional view of the tank. The horizontal broken line 10 may indicate the ground line. The portion below this line as indicated by A I refer to as the

45 bottom and the portion above the same as the container proper as indicated by B.

The container proper, or body portion thereof, as indicated by B, is of the same curvature as the container shown in my prior 50 Patent No. 1,622,787 of March 29, 1927 and

has all the advantages thereof. Since the manner of laying out this curve and constructing the tank is pointed out fully in the patent referred to I need not describe the same in detail here. It will suffice to say that the 55 body portion B is so shaped that at each point thereon the radius of curvature in a vertical plane, through a line normal to the shell at that point, is less than the radius of curvature in a plane at right angles to the first 60 mentioned plane and also passing through said normal line. It is also so shaped that the radii of the curvature at successive points from the top thereof toward the bottom in a vertical plane through lines normal to the shell at such points are successively shorter. It is also so curved that the radii of curvature at successive points from the top thereof 65 down to the bottom in planes at right angles to said vertical plane and also passing 70 through lines normal to the shell at such points are successively shorter from the top down to the point of the greatest horizontal diameter of such body portion and then successively longer from said point down to the 75 bottom thereof.

The container is in the shape of a solid of revolution about a vertical axis.

The bottom A is preferably substantially a circular segment of a sphere and may be supported in any suitable manner as by resting 80 on the ground 10.

While I have shown and described certain embodiments of my invention, it is to be understood that it is capable of many modifications. Changes, therefore, in the construction and arrangement may be made without departing from the spirit and scope of the invention disclosed in the appended claims, in which it is my intention to claim all novelty 85 in my invention as broadly as possible in view of the prior art.

What I claim as new, and desire to secure by Letters Patent, is:

1. A closed container substantially in the 90 shape of a solid of revolution about a vertical axis and having a supported segmental spherical bottom, said container so shaped that when substantially filled with a normal liquid 95 and containing a normal internal or vapor 100

pressure, the radius of curvature at each point on the shell above the supported bottom in a vertical plane, through a line normal to the shell at that point, equals the vertical tension at such point times the square of the radius of curvature in a plane at right angles to the first mentioned plane and also passing through said normal line, divided by the pressure at such point times the square of said second mentioned radius minus said vertical tension times said first mentioned radius.

2. A closed container substantially in the shape of a solid of revolution about a vertical axis and having a supported segmental spherical bottom, said container so shaped that at each point on the shell above the supported bottom the radius of curvature in a vertical plane, through a line normal to the shell at that point, is less than the radius of curvature in a plane at right angles to the first mentioned plane and also passing through said normal line.

3. A closed container substantially in the shape of a solid of revolution about a vertical axis and having a supported segmental spherical bottom, said container being so shaped that at each point on the shell above the supported bottom the radius of curvature in a vertical plane, through a line normal to the shell at that point, is less than the radius of curvature in a plane at right angles to the first mentioned plane and also passing through said normal line; said container also being so shaped that the radii of curvature at successive points on the shell from the top thereof down to the supported bottom in a vertical plane, through lines normal to the shell at such points, are successively shorter.

4. A closed container substantially in the shape of a solid of revolution about a vertical axis and having a supported segmental spherical bottom, said container so shaped that at each point on the shell above the supported bottom the radius of curvature in a vertical plane, through a line normal to the shell at that point, is less than the radius of curvature in a plane at right angles to the first mentioned plane and also passing through said normal line; said container also being so shaped that the radii of curvature at successive points on the shell from the top thereof down to the supported bottom in a vertical plane, through lines normal to the shell at such points, are successively shorter; and said container also being so shaped that the radii of curvature at successive points on the shell from the top thereof down to the supported bottom, in planes at right angles to said vertical plane, and also passing through lines normal to the shell at such points, are successively shorter from the top of said shell down to the point of its greatest horizontal diameter, and successively longer from said point down to the supported bottom.

5. A closed container substantially in the

shape of a solid of revolution about a vertical axis and having a supported segmental spherical bottom, said container being so shaped that the radii of curvature at successive points on the shell from the top thereof down to the supported bottom in a vertical plane, through lines normal to the shell at such points, are successively shorter; said container also being so shaped that the radii of curvature at successive points on the shell from the top thereof down to the supported bottom in planes at right angles to said vertical plane, and also passing through lines normal to the shell at such points, are successively shorter from the top of said shell down to the point of its greatest horizontal diameter and from such point are successively longer down to the supported bottom.

6. A closed container substantially in the shape of a solid of revolution about a vertical axis and having a supported segmental spherical bottom, said container being so shaped that the radii of curvature at successive points on the shell from the top thereof down to the supported bottom in planes at right angles to a vertical plane, and passing through lines normal to the shell at such points, are successively shorter from the top of the shell down to the point of its greatest horizontal diameter and from such point are successively longer down to the supported bottom.

7. A closed container for a volatile liquid substantially in the shape of a solid of revolution about a vertical central axis, every vertical central cross-section of which is an area bounded by a curve the bottom portion of which is rounded downwardly and of which the arcs from the bottom portion to the top central point have successively longer radii, the whole curve being a function of the weight and pressure of a liquid for which the container is designed substantially as set forth.

8. A closed container for a volatile liquid substantially in the shape of a solid of revolution about a vertical central axis, every vertical central cross-section of which is an area bounded by a curve the bottom portion of which is rounded downwardly and of which the arcs from the bottom portion to the top central point have different radii, the whole curve being a function of the weight and pressure of a liquid for which the container is designed substantially as set forth.

9. A closed container for a volatile liquid substantially in the shape of a solid of revolution about a vertical central axis, every vertical central cross-section of which is an area bounded by a curve the bottom portion of which is rounded downwardly and of which the arcs from the bottom portion to the top central point have different radii, those of the upper arcs being substantially longer than those of the lower arcs, the whole curve being a function of the weight and pres-

sure of a liquid for which the container is designed substantially as set forth.

10. A closed container substantially in the shape of a solid of revolution about a vertical axis and having a supported downwardly curved bottom, said container so shaped that when substantially filled with a normal liquid and containing a normal internal or vapor pressure, the radius of curvature at each point on the shell above the supported bottom in a vertical plane, through a line normal to the shell at that point, equals the vertical tension at such point times the square of the radius of curvature in a plane at right angles to the first mentioned plane and also passing through said normal line, divided by the pressure at such point times the square of said second mentioned radius minus said vertical tension times said first mentioned radius.

11. A closed container substantially in the shape of a solid of revolution about a vertical axis and having a supported downwardly curved bottom, said container so shaped that at each point on the shell above the supported bottom the radius of curvature in a vertical plane, through a line normal to the shell at that point, is less than the radius of curvature in a plane at right angles to the first mentioned plane and also passing through said normal line.

12. A closed container substantially in the shape of a solid of revolution about a vertical axis and having a supported downwardly curved bottom, said container being so shaped that at each point on the shell above the supported bottom the radius of curvature in a vertical plane, through a line normal to the shell at that point, is less than the radius of curvature in a plane at right angles to the first mentioned plane and also passing through said normal line; said container also being so shaped that the radii of curvature at successive points on the shell from the top thereof down to the supported bottom in a vertical plane, through lines normal to the shell at such points, are successively shorter.

13. A closed container substantially in the shape of a solid of revolution about a vertical axis and having a supported downwardly curved bottom, said container so shaped that at each point on the shell above the supported bottom the radius of curvature in a vertical plane, through a line normal to the shell at that point, is less than the radius of curvature in a plane at right angles to the first mentioned plane and also passing through said normal line; said container also being so shaped that the radii of curvature at successive points on the shell from the top thereof down to the supported bottom in a vertical plane, through lines normal to the shell at such points, are successively shorter; and said container also being so shaped that

the radii of curvature at successive points on the shell from the top thereof down to the supported bottom, in planes at right angles to said vertical plane, and also passing through lines normal to the shell at such points, are successively shorter from the top of said shell down to the point of its greatest horizontal diameter, and successively longer from said point down to the supported bottom.

14. A closed container substantially in the shape of a solid of revolution about a vertical axis and having a supported downwardly curved bottom, said container being so shaped that the radii of curvature at successive points on the shell from the top thereof down to the supported bottom in a vertical plane, through lines normal to the shell at such points, are successively shorter; said container also being so shaped that the radii of curvature at successive points on the shell from the top thereof down to the supported bottom in planes at right angles to said vertical plane, and also passing through lines normal to the shell at such points, are successively shorter from the top of said shell down to the point of its greatest horizontal diameter and from such point are successively longer down to the supported bottom.

15. A closed container substantially in the shape of a solid of revolution about a vertical axis and having a supported downwardly curved bottom, said container being so shaped that the radii of curvature at successive points on the shell from the top thereof down to the supported bottom in planes at right angles to a vertical plane, and passing through lines normal to the shell at such points, are successively shorter from the top of the shell down to the point of its greatest horizontal diameter and from such point are successively longer down to the supported bottom.

In witness whereof, I have hereunto set my hand this 15th day of October, 1928.
